(57) **CLAIM**

The ornamental design for a writing utensil, substantially as shown and described.

DESCRIPTION

FIG. 1 is an isometric view showing the front, part of one side and part of the top of the first embodiment of the writing utensil showing my new design;

FIG. 2 is an elevation view of the front, the rear being the mirror image thereof;

FIG. 3 is an elevation view of one side, the other side being the mirror image thereof;

FIG. 4 is an elevation view of the bottom thereof;

FIG. 5 is an elevation view of the top thereof;

FIG. 6 is an isometric view showing the front, part of one side and part of the top of a second embodiment thereof;

FIG. 7 is an elevation view of the front thereof;

FIG. 8 is an elevation view of the rear thereof;

FIG. 9 is an elevation view of one side, the other side being the mirror image thereof;

FIG. 10 is an elevation view of the bottom thereof; and,

FIG. 11 is an elevation view of the top thereof.

The stippled shading shown in the top in FIGS. 1, 2, 6, and 7 is meant to represent a contrast in color.
